UNITED STATES PATENT OFFICE.

DAVID A. LUMLEY, OF SAN JOSE, AND HERBERT A. BUTTS, OF NEAR SAN JOSE,
CALIFORNIA.

DESIGN FOR A SIGNAL CASE.

Application filed March 2, 1927. Serial No. 20,946. Term of patent 14 years.

To all whom it may concern:

Be it known that we, DAVID A. LUMLEY, a subject of the King of Great Britain and HERBERT A. BUTTS, a citizen of the United States, and residing, respectively, at San Jose, in the county of Santa Clara and State of California, and near San Jose, in the county of Santa Clara and State of California, have invented a new, original, and ornamental Design for Signal Cases, of which the following is a specification, refer-

ence being had to the accompanying drawing, forming a part thereof.

Figure 1 is a face view of a case showing our new design.

Figure 2 is a plan view of the same.

We claim:

The ornamental design for a signal case, as shown.

DAVID A. LUMLEY.
HERBERT A. BUTTS.
